[57] ABSTRACT

A commutator assembly mounted on a shaft for use with electrical rotary machinery having a plurality of round conductors with insulating coatings therearound overlaid around the rotary shaft, each of the conductors being disposed in parallel relationship with respect to the shaft and including a first portion facing towards the brush assembly of the machine, a second portion uprising from the shaft serving as the riser for electrical connection, and a third bent portion located therebetween, the number of conductors being selected depending upon the number of poles, and the diameter of the conductors being predetermined in order that the parallel portions are in close contact with adjacent conductors and with the shaft, the parallel portions having coaxially disposed surfaces void of insulating material so as to serve as commutator segments which may contact with the brush assembly; supporting means for securing the conductors to the shaft including a first portion made of an insulating material disposed in the spaces defined by the surfaces of the shaft and the adjacent conductors without covering the exposed surfaces of the conductors, and a second reinforcing portion made of insulating material for securing the bent portions to the shaft.

COMMUTATOR FOR ROTARY MACHINE

This is a continuation of application Ser. No. 64,325, filed Aug. 17, 1970 for "COMMUTATOR FOR ROTARY MACHINE," now abandoned.

The present invention relates to a commutator for rotary machines and more particularly to a commutator which is especially suited for use with miniaturized rotary machines and a method for manufacture the same.

A rotor of an electric rotary machine is provided with a commutator which comprises a plurality of segments assembled into a drumlike cylinder and insulation is placed between commutator segments and between the segments and the shaft to provide electrical insulation. The commutator segments are generally made of high drawn copper having a high conductivity and insulation is generally made by micanite having better quality. The segments are directly joined to the windings or indirectly joined to them through risers.

The commutator segments are circumferentially and equidistantly spaced apart from one another. The number of segments is determined depending upon the number of poles. To ensure the process of current reversal in the armature windings in combination with brushes, the commutator segments must be uniformly equidistantly spaced apart from one another and electrically insulated from one another. The commutators for miniaturized electric rotary machines having a small inertia must be of course miniaturized, but the arrangement and adjustment of the segments become exceedingly difficult. The greater the number of poles, the more difficult the arrangement and adjustment of commutator segments become.

It is one of the objects of the present invention to provide an improved commutator especially adapted for use with miniaturized electric rotary machines with commutator segments uniformly arranged.

It is another object of the present invention to provide a method for manufacture of a commutator comprising assembling a plurality of insulated conductors along the circumference of a circle into a drumlike cylinder and partially removing the insulator coatings of the conductors on the outer peripheral surface of the drumlike cylinder to provide the surfaces of the commutator segments for contact with brushes.

According to one aspect of the present invention, a plurality of insulated conductors are assembled along the circumference of a circle into a drumlike cylinder in close contact with one another and the insulator coatings of the conductors on the outer peripheral surface of the drumlike conductor assembly are partially removed to provide the surfaces of the commutator segments for contact with brushes.

According to another aspect of the present invention, a plurality of insulated conductors are overlaid around a shaft of a rotary machine or another shaft to be coupled to the shaft of the rotary machine in close contact with one another and the spaces between the conductors and between the conductors and the shaft are filled with an insulating adhesive agent so that the conductors may be securely held in position. The outer peripheral surface of the conductor assembly is concentrically machined by for example a grinding machine so as to remove the insulator coatings of the conductors.

According to another aspect of the present invention, a plurality of insulated conductors are overlaid around a jig or the like in close contact with one another into

a drumlike cylinder and one end faces of the conductors are machined so as to provide the surfaces of commutator segments for contact with brushes. The commutator thus assembled may be removed from the jig and mounted upon the shaft of a rotary machine.

According to another aspect of the present invention, an adhesive insulating material is filled into the spaces between the conductors and an adhesive reinforcing material may be applied to them. Alternatively, the conductors may be insulated with an insulator having adhesiveness so that the assembled conductors may be securely joined together by applying heat.

The present invention will become more apparent from the following description of the preferred embodiments taken in conjunction with the accompanying drawings, in which:

FIG. 1 is a diagrammatic front view of a first embodiment of a commutator in accordance with the present invention;

FIG. 2 is a sectional view taken along the line A—A of FIG. 1;

FIG. 3 is a schematic view illustrating a rotor provided with the commutator shown in FIGS. 1 and 2;

FIG. 4 is a front view of a second embodiment of a commutator in accordance with the present invention;

FIG. 5 is a sectional view taken along the line B—B' of FIG. 4;

FIG. 6 is a schematic view illustrating a rotor carrying the commutator shown in FIGS. 4 and 5; and

FIG. 7 is a fragmentary view illustrating the joint between the adjacent conductors of the commutator in accordance with the present invention.

Referring to FIG. 1, along the axis of a shaft 10 are circumferentially arranged a plurality of round conductors 11, 12, 13, 14 and 15 having the insulators 11', 12', 13', 14' and 15' coated therearound. The conductors 11—15 are L-shaped as best shown in FIG. 2 to provide the upright portions which serve as the risers. The diameters of the insulated conductors 11—15 must be suitably selected. More specifically, when the diameters are too small, the conductors arranged along the axis of the shaft 10 would be spaced apart from one another too much while when the diameters are too greater, the conductors 11—15 would not be disposed in a symmetrical arrangement to the shaft 10. That is, the diameters must be so selected that the conductors 11—15 may be arranged around the shaft 10 in such a manner that they are in close contact with one another and with the shaft 10. A suitable member such as a sleeve may be interposed between the shaft 10 and the conductors 11—15. An insulating material 16 such as epoxy resin may be filled in the spaces between the conductors and shaft so that the conductors may be securely held in position. In order to further secure the attachment of the conductors 11—15, suitable reinforcing member 17 may be applied to the bent portions of the conductors 11—15.

The conductors 11—15 arranged securely around the shaft 10 are concentrically machined to partially remove their insulators 11'—15' and to have the machine surfaces 12₁ of the conductors 11—15 laid in a cylindrical surface concentric with the shaft 10 as shown in FIGS. 1 and 2. Therefore, the machined surfaces 12₁ of the conductors 11—15 serve as the surfaces of the commutator segments or bars with which make contact the brush assemblies (not shown). The exterior of the assembly of the conductors 11—15 are concentrically

symmetrically machined so that the conductors remain electrically insulated with one another and the shaft 10, whereby the commutator segments or bars may be provided in a simple and effective manner. FIG. 3 shows a rotor provided with the commutator of the type described with reference to FIGS. 1 and 2. The commutator 100 is mounted on the shaft 10 concentrically of the rotor 101 and the brushes 102 and 103 are made in contact with the commutator segments radially of the commutator.

The second embodiment of the present invention is illustrated in FIGS. 4 and 5. Eighteen conductors 21-38 coated with the insulating coatings 21' - 38' are arranged around the peripheral surface of a jig (not shown) whose diameter is greater than that of the shaft. 15 As explained above, the diameter of the conductors 21-38 must be so selected that the conductors may be overlaid in close contact with one another and the jig. The overlaid conductors 21-38 are securely held in position by means of the insulating material as described 20 in the first embodiment with reference to FIGS. 1 and 2 while the reinforcing member 39 may be applied to the bent portions of the L-shaped conductors. Since the commutator assembly must be removed from the jig, means must be provided in order to prevent the insulating material from being adhered to the jig. For example 25 instead of the insulating material, the insulators 71' and 72' of the conductors 71 and 72 shown in FIG. 7 may be imparted with thermal adhesiveness so that when heat is applied after the conductors are overlaid around 30 the periphery of the jig or the like, they may be securely adhered to each other at 73 in FIG. 7 and held in position. In this manner, the commutator assembly may be readily removed from the jig or the like.

Referring back to FIGS. 4 and 5, the end faces of the 35 conductors 21-38 serve as the surfaces of the commutator segments. For this purpose, the end faces of the conductors are ground to give a fine surface finish so that the brush assemblies may smoothly make contact with them. The commutator segments are electrically 40 insulated by the insulator coatings 21' - 38' of the conductors and are uniformly arranged. FIG. 6 is a schematic view illustrating a rotor provided with the commutator assembled in the manner described with reference to FIGS. 4 and 5. A rotor 201 and a commutator 45 202 are carried by a shaft 200. Since the commutator 202 which is slidably in contact with the brushes 203 and 204 is not assembled directly around the shaft 200, it must be mounted upon the shaft 200 directly or indirectly utilizing for example a sleeve in any suitable 50 manner.

According to the present invention, the commutator segments may be uniformly arranged so that the adjustment after the assembly is not required. No short-circuit between the commutator segments will occur 5 because they are electrically insulated from one another by their own insulator coatings. Furthermore, the commutators may be miniaturized with a high degree of accuracy so that the rotary machines themselves may be miniaturized. What is claimed is:

10 1. A commutator assembly mounted on a shaft for use with an electric rotary machine having a rotor rotatable with the shaft comprising:

a plurality of round conductors overlaid around said rotor shaft and having electrical insulating coatings therearound, each of said conductors being parallel to said shaft and comprising, a portion facing towards a brush assembly of said machine, a portion uprising from the shaft serving as a riser for electrical connection, and a bent portion located therebetween, the number of said conductors being selected depending upon the number of poles, and the diameter of said conductors being predetermined in order that said parallel portions are in close contact with adjacent conductors and with the shaft, said parallel portions having coaxially exposed surfaces void of insulating material so as to serve as commutator segments which make contact with the brush assembly;

supporting means for securing said conductors to the shaft comprising, a first portion made of an insulating material disposed in the spaces defined by the surfaces of the shaft and the adjacent conductors without covering said exposed surfaces of each conductor, and a second reinforcing portion made of insulating material for securing said bent portions to the shaft.

2. A commutator as defined in claim 1 wherein said exposed surfaces of said conductors are concentrically disposed one with respect to the other and each having a smooth finish to make contact with said brush assembly during operation.

3. A commutator as defined in claim 1, wherein said plurality of insulated conductors are arranged in a cylindrical configuration.

4. A commutator as defined in claim 1 wherein said plurality of insulated conductors have coatings of an adhesive insulating material disposed on their unexposed surfaces facing toward said shaft and the adjacent conductors.
